DESIGN FOR A DRESS ENSEMBLE

Harry Presser, New York, N. Y.

Application March 4, 1939, Serial No. 83,324

Term of patent 3½ years

To all whom it may concern:

Be it known that I, Harry Presser, a citizen of the United States of America, residing in city of New York, county of New York, and State of New York, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a rear view of Fig. 1.

Fig. 3 is a front view of the dress member of the ensemble.

Fig. 4 is a rear view of Fig. 3.

The characteristic feature of my design resides in the combination on the ensemble disclosed of the specific velvet panels coming down the front portion of the coat in association with the matching velvet panel on the front waist portion of the dress as shown.

I claim:

The ornamental design for a dress ensemble, substantially as shown and described.

HARRY PRESSER.
